(57) **CLAIM**

The ornamental design of a display panel with a computer icon, substantially as shown and described.

DESCRIPTION

FIG. 1 is a front view of a display panel with computer icon, showing our new design; and,

FIG. 2 is a front view of a second embodiment thereof. The broken lines showing portions of the computer icon are included for the purpose of illustrating environmental structure and form no part of the claimed design. The outer solid line circle represents a portion of the display panel which forms part of the claimed design.
